UNITED STATES PATENT OFFICE.

WILLIAM E. STEVENS, OF NEW HAVEN, CONNECTICUT, ASSIGNOR TO SARGENT & COMPANY, OF NEW HAVEN, CONNECTICUT, A CORPORATION OF CONNECTICUT.

DESIGN FOR CASKET-TRIMMING.

SPECIFICATION forming part of Design No. 37,131, dated September 13, 1904.

Application filed August 18, 1904. Serial No. 221,297. Term of patent 14 years.

To all whom it may concern:

Be it known that I, WILLIAM E. STEVENS, of the city and county of New Haven, in the State of Connecticut, have invented a new, original, and ornamental Design for a Casket-Trimming, of which the following is a specification when taken in connection with the accompanying drawings, which form a part thereof, and in which—

10 Figure 1 represents a front elevation of a casket-trimming embodying my new, original,

and ornamental design; and Fig. 2, an end view of the same.

What I claim as new, and desire to secure by Letters Patent, is—

15 The ornamental design for a casket-trimming, as shown.

WILLIAM E. STEVENS.
